WHEELED SCRAPER

Joseph H. Slaker and De Mar A. Palmer, Aurora,
Ill., assignors, by mesne assignments, to Western-Austin Company, Aurora, Ill., a corporation of Illinois

Application September 12, 1932, Serial No. 632,706

37 Claims. (Cl. 37—129)

The present invention relates generally to scrapers such as are employed for grading, leveling and digging operations, and has particular reference to scrapers of the type which are mounted on wheels or crawler treads and are adapted to be propelled by a tractor or other pulling vehicle.

One of the general objects of the invention is to provide a scraper of this type characterized by improved mechanism for moving the scraping pan or scoop between the various positions which it assumes relatively to the implement frame. The pan has three principal positions; a loading or digging position where the cutting edge of the pan is engaging the soil for loading the soil in the pan; a transport position where the pan is raised out of contact with the soil for carrying its contained load of soil to a point of dumping; and, a dumping position where the pan is tipped for dumping its contained load of soil.

With reference to the mechanism for moving the pan between its three positions, another object of the invention is to provide improved power lift mechanism utilizing kinetic energy for raising the pan from digging position to transport position and for tilting the pan from transport position to dumping position. This improved power actuated lifting mechanism dispenses with the necessity of springs and equivalent arrangements which have heretofore been widely employed for lifting the loaded pan from digging position to transport position. In prior constructions in which sufficient potential energy is stored in the springs to raise the fully loaded pan from digging position to transport position, numerous difficulties and objections are encountered, such as the difficulty in some cases of holding the digging pan down in proper digging engagement with the soil, the necessity in some cases of maintaining the power transmission clutches in a continuously slipping engagement during the entire digging operation for resisting the tendency of the springs to elevate the pan, the likelihood of the springs weakening becoming incapable of raising a heavily loaded pan, etc. All of these difficulties and objections are avoided in the present construction, which uses no springs for effecting any of the movements of the pan.

This power operated lifting mechanism preferably derives its power from the traction energy of the supporting wheels or crawler treads (although the invention is not limited to a construction deriving its power only from traction energy) and another object of the invention is to

provide improved mechanism for transmitting this traction energy to the pan. In this regard, it is one of the objects of the invention to provide improved clutch mechanism for controllably transmitting this traction power to the lifting mechanism. This clutch mechanism is preferably of the friction type and embodies improved means for maintaining the frictional engagement of the clutch through its predetermined range of movement notwithstanding the fact that the clutch engaging control member moves directly with the driven clutch element. This improved construction avoids the tendency, present in some prior constructions, for the frictional engagement of the clutch to diminish with the rotative movement of the driven clutch element, requiring continued and further actuation of the clutch actuating devices to maintain the clutch in power transmitting engagement.

A further object of the invention is to provide improved locking means, preferably of the toggle type, for releasably holding the pan raised in its transport position. This improved locking mechanism functions to hold the loaded pan in transport position, after an initial operation of the power lift mechanism for raising the pan to this position from its digging position, and preparatory to a later operation of the power lift mechanism for raising the pan to dumping position; and also functions to hold the empty pan in transport position, after the first lowering of said pan from dumping position to transport position and preparatory to the second lowering of said pan from transport position down to digging position.

A further object of the invention is to provide an improved arrangement of control apparatus and connections whereby the actuation of a single control member is operative selectively to cause engagement of said clutches or to cause the release of said locking mechanism. In thus simplifying the control operations necessary to be performed, the implement is made more adaptable to use in tandem or train operation, and the control of one or more implements by a single operator or by the driver of the tractor is facilitated.

A further object of the invention is to provide improved means for controlling the position of the pan when digging and when being transported, and for controlling the movement of the pan between digging position and transporting position. This improved control means is directly mechanical and positive in its operation, and independent of any varying spring pressures, for

efficiently holding the pan in proper digging position against the action of the large stresses bearing against the cutting edge of the pan, and for holding the pan in transport position against the action of the load of soil in the pan tending to tilt the latter.

The construction embodies a draft connection between the pan and a forward portion of the implement frame for sustaining the draft stresses acting against the cutting edge of the pan, and it is a further object of the invention to provide improved means for releasing this draft connection when the pan is to be upended for dumping. In this regard, it is one of the objects to provide an improved construction and arrangement which will effect this release of the draft connection automatically in the movement of the pan.

Another object is to provide improved means for cushioning or yieldingly retarding the drop of the pan from dumping position to transport position, so as to avoid objectionable shock and racking of the mechanism. In this regard, another object of the invention is to provide an improved checking mechanism which will automatically hold the pan in its dumping position, without attention on the part of the operator, for a sufficient interval to insure complete dumping of the load, even when the load consists of sticky material.

Another object of the invention is to provide an improved scraper of this general type having an improved relation of end gate for approximately closing the pan during transport, which end gate is movable automatically to different positions in the loading and dumping positions of the pan.

Other objects and advantages of the construction will appear from the following detailed description of a preferred embodiment thereof. In the accompanying drawings illustrating such embodiment:

Figure 1 is a perspective view of the scraper, with the pan raised to transport position;

Figure 2 is a plan view of the construction, a portion of the frame being broken away;

Figure 3 is a fragmentary side view showing the pan lowered to digging position, the rear portion of the view corresponding to a longitudinal section taken just inside the adjacent wheel and its clutch mechanism;

Figures 3A, 3B and 3C are schematic diagrams for better illustrating the forces and movements involved in the lifting of the pan from digging position to transport position;

Figure 4 is a longitudinal sectional view on a slightly smaller scale than Figure 3, illustrating the pan raised to its transport position;

Figure 5 is a view on approximately the same scale as Figure 3, illustrating the pan upended to dumping position;

Figure 6 is a transverse sectional view taken approximately on the plane of the line 6-6 of Figure 2, illustrating some of the control connections for engaging the clutches and for releasing the toggle locks;

Figure 7 is a fragmentary perspective view illustrating the relation of the lost motion collars which actuate the toggle lock tripping lever, and illustrating one method of fastening the chains which govern the cutting depth of the pan when in the digging operation;

Figure 8 is a detail view illustrating one end of the axle and showing the mounting of the

wheel, lifter arm, guide link and one embodiment of clutch on this end of the axle, corresponding approximately to a vertical section taken in rear of the wheel axis and looking forwardly;

Figure 9 is a transverse sectional view through the embodiment of clutch mechanism illustrated in Figure 8;

Figure 10 is a view similar to Figure 8, illustrating a modified construction of clutch;

Figure 11 is a transverse sectional view through this modified construction of clutch;

Figure 12 is a view similar to Figures 9 and 11, illustrating another modified construction;

Figure 13 is a fragmentary detail view illustrating an arrangement providing for the automatic release of the draft connection between the pan and the implement frame, preparatory to the lifting of the pan to dumping position;

Figure 14 is a fragmentary side view of a modified arrangement of the control or actuating parts, adapted to transmit equalized operating energy to the two power clutches;

Figure 15 is a front elevational view thereof, a part being shown in section;

Figure 16 is a horizontal sectional view taken approximately on the plane of the line 16-16 of Figure 15;

Figure 17 is a fragmentary plan view illustrating another embodiment of our invention using an end gate for the front end of the pan;

Figure 18 is a fragmentary vertical sectional view, illustrating the normal position of this end gate when the pan is in transport position;

Figure 19 is a similar view illustrating the position which the end gate may assume when the pan is tilted up to dumping position;

Figure 20 is a similar view, illustrating more of the pan, and showing how the pile of earth entering the pan during loading can raise the end gate to a non-obstructing position;

Figure 21 is a fragmentary side view, illustrating the use of a modified construction of checking cylinder; and

Figure 22 is a detail sectional view through this cylinder, on a larger scale.

Referring first to Figures 1 and 2, the main supporting frame, indicated generally at F, is supported by ground engaging elements typically represented by the two side wheels 20, 20. While it is preferable for most conditions of operation to have the frame supported on wheels, it may be desirable for operating in extremely soft soil, or under other adverse conditions, to have these ground engaging elements in the form of creeper treads, such as are commonly used on tractors and heavy duty dump wagons. If desired, the front end of this main frame may have swiveled mounting on a steerable front truck. Said main frame F is preferably built up of two channel beams 21, which are bent to have the configuration illustrated in Figures 1 and 2, viz., having closely spaced parallel front portions 21a, which are then bent outwardly to form diverging side portions 21b and which are then bent rearwardly to form widely spaced parallel rear portions 21c, between which the load carrying pan is mounted. It will be understood that separate bar sections can be joined together to form these portions of the frame, if desired. Suitable cross plates, generally indicated at 22 and 23, connect the forward portions 21a of the frame channels and form an open box-like structure therebetween, in which certain of the operating parts are mounted. Extending forwardly from the frame structure are two converging plates 25, which

form a draft attachment having a vertical series of holes 26 enabling a draft clevis 27 to be suitably positioned at any desired height for the most effective transmission of draft to the scraper. Referring to Figure 2, the rear ends of the frame bars are cross-connected by a heavy tube 28 which may be riveted or welded to the ends of the bars 21, these points of attachment also being reinforced by diagonal gusset plates 29 which are riveted or welded to the tube and to the frame bars. A split sleeve 34 is riveted or welded to the intermediate portion of the transverse tube 28 and has rearwardly extending ears 34a for receiving a draft pin 35 (Figure 4) by which a hitch connection can be established to another trailing scraper. The front part of the widened rear portion of the frame is also cross-braced by another tube or channel, 36, (Figures 2 and 6) which has its ends riveted or welded to the side channels 21, 21 adjacent to the points where these channels are bent to form the forwardly converging portions 21b. An operator's platform 37 is built above this converging portion of the frame structure, consisting of a series of longitudinal slats 38 secured to cross bars 39 which have their ends suitably attached to the frame channels. A guard rail 41 is suitably anchored to the frame structure to extend around the forward portion of the operator's platform.

The wheels or other ground engaging elements 20 have rotatable mounting on a transverse axle 44, preferably on roller bearings, as illustrated in Figure 8. As shown in the latter figure, the axle 44 has rotatable mounting at each side of the frame in bearing brackets 45 which are bolted to the top flanges and to the webs of the two side channels 21. Referring to Figure 1, the intervening span of the axle is preferably arched or bowed upwardly as indicated at 44a in order to avoid the axle obstructing the movement of soil back into the pan. As will be hereinafter described, improved clutch devices are associated with each wheel or ground engaging element 20 whereby the rotative movement of said elements can be transmitted to the axle 44 for causing the axle to lift the pan from digging position to transport position, and from transport position to dumping position. While it is preferable to employ a rotating axle through which power is transmitted from the clutches to the lifting mechanism, in order to compel both lifting mechanisms to operate simultaneously and to the same degree, nevertheless the construction may be such as to transmit power from the clutches to the lifting mechanism independently of the axle.

The pan is generally indicated at 48 and is movably disposed between the widely spaced rear portions of the frame channels. The pan, in its preferred construction, has an open front end, a substantially flat bottom, and upwardly extending rear and side walls. The pan is loaded through the front end and is dumped through the front end. The cutting edge of the pan is reinforced by a plate 49 riveted or bolted across the bottom of the pan and having upwardly extending end portions 49a riveted to the side walls of the pan. The rear wall is preferably formed as a separate plate having flange portions riveted to the bottom and side walls of the pan, and having its upper edge reinforced by a transverse angle iron 52. Bolted to the bottom of the pan, at spaced intervals across its width, are inclined runners 54. As shown in Figure 3, when the pan

is in its loading or digging position these runners slide on the soil along the bottom of the cut and assist in holding the pan at the proper cutting angle. Said runners can be adjusted relatively to the pan for changing the cutting angle of the pan, as by inserting filler plates between the pan and the rear leg of each runner.

Figures 3, 4 and 5 illustrate the three principal positions into which the pan is movable:—digging, transporting and dumping. There are three principal mechanisms or elements which effect the movement of the pan between these positions and which properly hold and guide the pan, viz: (1) The power lift mechanism comprising a rotatable power lift arm 56 and a lifting link 57 connecting this arm with the pan; (2) the draft connection in the form of a link 58 which establishes a releasable draft connection between the pan and a forward portion of the frame; and (3) the controlling or guiding link 59 which assists in holding the pan in the proper digging position when down and which also aids in holding the pan approximately level when in transport position. It will be understood that each of these three mechanisms or devices 56—57, 58 and 59 is duplicated on each side of the pan. The side walls of the pan are provided with substantially V-shaped notches 61 extending down from the upper edges of these side walls, which notches embrace or accommodate the axle 44 when the pan is in transport and dumping positions. Each lifting link 57 is preferably slightly bent or curved intermediate its ends and the inner side of this curve constitutes an arcuate bearing surface 57a (Figure 3). When the pan is moving from transport position to dumping position this bearing surface 57a bears against the cylindrical bearing surface 62 of a collar 63, which collar is mounted on the axle 44 just inside of the adjacent axle bearing bracket 45 (Figure 40 8). When the pan is in transport position, this arcuate bearing surface 57a is preferably slightly spaced from said bearing surface 62. The arcuate bottom edges of the substantially V-shaped notches 61 may be arranged to have bearing engagement against the bearing surfaces 62 of collars 63 when the pan is in transport and dumping positions, or these bottom edges may remain spaced from said bearing surfaces 62 when the pan is in either of these positions, the pan operating entirely satisfactorily in constructions in which this spaced relation is maintained.

Referring in more detail to the lifting mechanism 56—57, the lower end of the lifting link 57 is pivotally connected to a pivot stud 67 which is anchored in a reinforcing plate 68 secured to the lower forward portion of the pan. The upper end of said link 57 is pivotally mounted on a pivot bolt or stud 69 which is supported in the lifting arm 56. This lifting arm is of sector shape, as best shown in Figure 5, being preferably constructed in the form of a radial web or flange projecting outwardly from the collar 63 (Figure 8). The collar 63 is secured fast to the axle 44 and whenever power driven rotation is transmitted to the axle the collar 63 and lifting arm 56 rotate directly therewith. As previously remarked, the wheels or other ground engaging elements 20 are operative to transmit rotative movement to the axle 44 through the engagement of clutches which are generally indicated at 72 and which will be hereinafter described. The pivot stud 69 connecting the lifting link 57 with the lifting sector 56 is disposed adjacent to the rearward end of said sector, and the link extends

down to its connection with the pan around the rear side of the axle 44. The forward portion of said sector is provided with an upwardly and rearwardly curved hook 75 forming a curved socket 76. A toggle mechanism 77, 78 is adapted to cooperate with the hook 75 in holding the pan in its transport position. This toggle mechanism comprises a long rearward link 77 and a short forward link 78, the two links being pivotally connected together at a knuckle pivot 79. The forward link 78 is secured to a rotatable pivot shaft 81 which is mounted between an outer bracket plate 82 and an inner bracket plate 83, both of which are suitably secured to the frame structure. At the rear end of the rearward link 77 is a pin 86 which is adapted to engage in the socket 76 under the hook 75. Preferably the rear link 77 is constructed of two spaced bars so that it is in effect a double link, and, likewise, the forward link 78 is also composed of two spaced bars. Hence, the two bars of the rearward link 77 form a yoke structure which straddles the arcuate rim of the sector-shaped lifting arm 56, with the transverse pin 86 in position to engage in the socket 76 under the hook 75. This arcuate peripheral portion of the lifting sector is widened slightly, adjacent to and around the socket 76 for giving a greater area of bearing engagement for the pin 86 when in said socket. The toggle 77, 78 is adapted to be folded to a forward and downward position as illustrated in Figure 4, in which position a straight line drawn between the pins 79 and 86 passes below or through the axis of the pivot shaft 81, whereby this past center relation holds the toggle locked against rearward pull exerted by the lifting sector 56 against pin 86. The toggle assumes this condition when said lifting sector 56 has been swung forwardly to the position illustrated in Figure 4, at which time the lifting link 57 has raised the pan 48 to transport position. The locked condition of the toggle with the cross pin 86 engaging in the hook socket 76 prevents backward oscillation of the lifter 56, thereby holding the pan in transport position. To drop the pan to digging position it is only necessary to break the toggle by effecting such upward movement of the forward link 78 as will carry the toggle pivot 79 up beyond its past center relation, whereupon the lifter 56 can rotate rearwardly for permitting the pan to lower. In the dumping operation illustrated in Figure 5, the lifting sector continues its forward rotation beyond the position illustrated in Figure 4, and in such further forward movement the forked end of the toggle, together with its cross pin 86, merely rides on the arcuate upper surface of the moving lifter. The influence of a spring is constantly exerted on the toggle, tending to swing the toggle links into the locked position illustrated in Figure 4, so that whenever the lifting member 56 is given power actuation for raising the pan from digging position to transport position the resultant forward rotation of the hook projection 75 will permit the toggle mechanism to swing forwardly automatically under this spring action, whereby the toggle will automatically lock. This spring action is obtained by rigidly fastening the two spaced bars of the forward link 78 to the pivot shaft 81 and by extending this pivot shaft inwardly or outwardly from the inner or outer bracket plates 83, 82 to carry a torsion spring 87 thereon, as shown in Figures 2 and 6. One end of this spring is anchored to the pivot shaft 81 and the other end is anchored to the adjacent bracket plate 82 or 83, whereby

the torsion of the spring tends constantly to rotate the pivot shaft 81 and link bars 78 in a forward direction.

The cutting depth to which the pan can be lowered can be varied through adjustments established through chains or like flexible members 91, there being one of these chains at each side of the pan. The rear end of each chain is linked to an arm 92 which projects radially from the hub of collar portion 62 of the lifting segment 10 56, the arm having reenforced connection with said collar as best shown in Figure 8. The links at the forward end of said chain pass down through a keyhole slot 94 which is formed in a horizontal plate 38a extending rearwardly from the side portion of the operator's platform. The effective length of each chain 91 can be varied by engaging different ones of the links in the narrow portion of the keyhole slot, and in this manner the extent to which the arm 92 and lifter 20 56 can swing backwardly in the lowering movement of the pan can be adjusted.

All of the above described parts having to do with the pan moving and locking operations performed through the link 57 are disposed in the 25 space between the inner side of the frame channel 21 and the side wall of the pan, and all of these parts are duplicated at the other side of the pan.

Referring now to the control mechanism which 30 effects the release of the two toggle mechanisms 77, 78 at opposite sides of the pan, and which also controls the engagement of the two clutches 72 associated with the respective wheels 20, this control mechanism preferably comprises a single 35 operating lever 101 which is mounted to swing about the axis of a transverse control shaft 102. As shown in Figure 6, the end portions of said shaft are rotatably supported in bearing brackets 103 which are secured to the frame channels 21 40 or to the plates 38a, and the ends of said shaft projecting outwardly beyond these bearings have crank arms 104 secured thereto. These crank arms have linked connection with the parts which cause engagement of the two power 45 clutches 72, which will be later described. Rotatably mounted on the shaft 102 are two sleeves 105, 105 which have upwardly extending parallel arms 106, 106 at their inner ends. The upper portions of these spaced arms converge together 50 and become the control lever 101. Mounted in the space between these lower arm portions 106 is a sector-shaped arm or plate 107 having a lower hub portion which is rigidly pinned to the shaft 102. An inertia responsive latch 108 cooperates 55 between the lever 101 and the plate 107, whereby when the lever 101 is drawn forward relatively slowly the latch compels the plate 107 to move therewith, but when the lever is jerked forward quickly the inertia latch is released for permitting the lever to move forwardly independently of the plate 107. The latch 108 normally rides on an arcuate periphery of the plate 107, in position to engage against a shoulder 109 on said plate when the lever is drawn forwardly. Said 65 latch is pivotally mounted between the lower spaced arm portions 106, 106 of the lever on a transverse pivot pin 111, and projecting beyond and up the back side of the lever is an extension of said latch having a weighted end 108a. A light 70 spring 112 is coiled about the end of the pivot pin 111 and has one end hooked to the lever and the other end hooked to the weighted extension 108a, whereby the latter extension is normally pressed forwardly against the back side of the lever with 75

the latch nose 108 down in position to engage the shoulder 109. A U-shaped strap 114 is secured to the weighted extension and extends forwardly around the front side of the lever to limit the range of separating movement between the lever and the weighted extension when the lever is jerked forward quickly. A transverse stop 115 (best shown in Figures 14 and 15) is secured to the rear portion of the plate or arm 107 and extends across the back sides of the lower spaced arm portions 106, 106 of the lever to prevent rearward separation of the lever from said plate. Each time that the lever is moved forwardly, either quickly or slowly, the sleeves 105, 105 move directly therewith, and extending upwardly from the end portions of said sleeves are two arms 118, 118 which have tension springs 119 connected thereto and extending rearwardly to suitable points of attachment on projections rising from the plates 38a. These tension springs always tend to return the sleeves 105 and the lever 101 back to their normal retracted position, and the lever in returning to such position engages the cross bar stop 115 on the sector plate 107 and returns the latter, together with the shaft 102, back to their normal positions. Fastened on the end portions of said sleeves 105, 105 are collars 122, which are preferably secured to the sleeves by set screws 123 or by any other suitable means enabling the angular positions of the collars to be adjusted relatively to the sleeves. Disposed adjacent to said latter collars are co-operating collars 124 within which the sleeves are freely rotatable. These rotatable collars carry rearwardly extending bent levers 125, each of which has a T-shaped outer end adapted in its upward swinging movement to engage the under sides of the toggle link bars 78 for swinging said toggle links to released position. Referring to Figure 7, each collar 122 has a lug or shoulder 127, and each companion collar 124 has a co-operating lug or shoulder 128 projecting into the path of movement of the shoulder 127. The normal spacing between the lugs 127 and 128 is such that they do not engage for transmitting motion from the collars 122 to the collars 124 and their toggle releasing levers 125 until after the lever 101 has been moved forwardly a distance corresponding to its range of movement for causing engagement of the clutches 72, which range of movement in the illustrated construction is approximately 35°. That is to say, if the actuation of said lever is to cause engagement of the clutches it is drawn forward comparatively slowly so as to cause movement of the sector plate 107, shaft 102 and levers 104 directly therewith, and during this range of clutch engaging motion, illustrated as being of approximately 35°, there is no motion transmitted from the collars 122 to the collars 124, owing to the lost motion relation between the lugs 127, 128; whereas, if the actuation of said lever is to effect the releasing of the toggles, it is drawn forward quickly so as to throw the inertia latch 108 to inoperative position, whereby the sector plate 107 does not move therewith, and in this operation after the lever 101 has moved through approximately 35° of its motion the lugs 127, 128 engage and thereafter the T-shaped levers 125 are swung upwardly for releasing the toggles.

Referring now to the clutches 72 and their actuating connections, the lower end of each arm 104 carries a pivot 131 (Figure 3) to which a rearwardly extending link 132 is connected. Said link comprises a threaded clevis portion 133 into which a threaded front portion of the link screws, whereby the effective length of the link can be easily adjusted. The rear end of each link 132 is pivotally connected at 135 to a lever 136 which is pivoted at its lower end on a pivot bolt 137 carried by the frame channel. These parts are disposed between the frame channel and the adjacent wheel. The upper end of the lever 136 carries a pin 138 to which the forward ends of two links 139 and 139a are pivoted. The link 139 has an angularly projecting stop shoulder 139b at its end which is adapted to engage the back side of the companion link 139a so as to limit the relative spreading movement between said links, for a purpose which will be presently described. The rear ends of said links are pivotally connected by pins 141 to two shifting links 142, both of segmental shape, which form an expandable and contractible semi-ring, adapted in its expanded form to establish an arcuate guide track for exerting pressure against the clutch operating lever which expands the clutch band. The two segmental links embrace the axle 44 and the rear ends of said links are pivotally connected by a pivot pin 143. The pivotal connection between these two links at pin 143 is preferably such as to leave a smooth arcuate contour between the two links at their point of juncture when the links are expanded, the joint shown in Figure 8 comprising a tongue extending from one link into a bifurcated end of the other link. The connecting pin 143 projects outwardly from the side of the two links and is pivotally mounted in the upper end of a swinging lever 144, which has pivotal mounting at its lower end on a pin 145 carried by the adjacent frame channel. A stop lug 146 projects outwardly from the top of the frame channel into the path of movement of the lever 144 for limiting the rearward swinging movement of said lever. The clutch operating lever which expands the clutch band in response to the expansion of the links 142 is indicated at 148 in Figure 9, this lever having a roller 149 at its swinging end which is adapted to track along the outer surface of the ring segments 142 in the 30 rotational movement of the driven clutch member. Normally the parts are in the position illustrated in Figure 4 (and also illustrated in inner dotted lines in Figure 9), at which time the ring segments 142 are collapsed and the clutch operating lever 148 is in the inner dotted line position. In this normal or transport position, the roller 149 on the end of the said clutch operating lever 148 occupies the dotted line position designated A in Figure 9. When the pan has been swung up to dumping position said roller, with its arm 148, has moved toward or into the dotted line position designated B; and when the pan has been lowered to digging position said roller, with its arm 148, has moved toward or into the dotted line position designated C. Starting with the pan in its normal transport position, rearward thrusting movement transmitted through link 132 and lever 136 to the ring segments 142 causes the connected portions of the segments to press outwardly against the roller 149, swinging it and its lever 148 outwardly to clutch engaging position, indicated by the outer dotted line position of said lever. Continued motion transmitted to the ring segments 70 causes them to expand outwardly to the positions indicated in the outer dotted circles in Figure 9. In this position they define a semi-ring substantially concentric with relation to the axle 44, being prevented from spreading further by the en-

gagement of the shoulder 139b against the back side of the link 139a. With the engagement of the clutch and the concurrent expansion of the ring segments to this position, the clutch engaging lever 148 and roller 149 swing up toward or into dotted line position B, corresponding to dumping position of the pan. Notwithstanding the fact that the lever 148 swings bodily with the driven clutch element, it will be noted that the expanded ring segments 142 form a control member which is operative to maintain this lever in its position of maximum clutch engagement during such rotative movement with the driven clutch element. This follows by virtue of the co-action of the supporting lever 144 with the stop lug 146, such limiting the motion of the segments 142 to the left and hence preventing the segments from folding up and slipping under the roller 149 when the roller moves upwardly toward position B. Likewise when the roller is in digging position C, the coaction of lever 144 with stop 146 compels the segments to expand outwardly against said roller when the clutch is to be engaged.

The driving element of the clutch comprises a drum 154 having an outer peripheral flange 155 enclosing the clutch parts. This driving element is suitably secured to the hub of the adjacent wheel or other ground engaging element 20.

The driven element of the clutch comprises a disc 156 which closes the open face of the drum 154 and which has a central hub portion 157 suitably keyed to the axle 44. A plurality of shelf brackets 158 project inwardly from the disc 156 at angularly spaced points for supporting a clutch band 159. A suitable facing 162 on the outer surface of said band is adapted to be forced into gripping engagement with the inner surface of the flange 155 when the band 159 is expanded.

The clutch actuating lever 148 is secured to a shaft 163 journaled in the disc 156 and extending into the clutch housing. At its inner end this shaft has a cam 164 secured thereto which is adapted to act against a pressure block 165 secured to one end of the clutch band 159. The other end of the clutch band has a lug 166 secured thereto, to which a link 167 is pivoted at 168. The other end of said link is pivoted to a slide block 171 which has adjustable mounting in a slotted guideway 172 formed in the disc 156. An adjusting screw 174 disposed on the outside of the clutch assembly has threaded mounting in a guide boss and has its inner end connected with the slide block 171, whereby manipulation of said adjusting screw is operated to shift said slide block inwardly or outwardly and thereby to expand or contract the clutch band for adjustment purposes. A plurality of tension springs 176 are connected between the shelf brackets 158 and suitable lugs projecting from the clutch band, so as normally to retract said band out of clutching engagement with the external flange 155.

The movement of the pan in dumping direction, Figure 5, is limited by the forward edge of each lifting segment 56 striking a stop shoulder 178 which projects inwardly a short distance from the inner side of each frame channel. The dumping will ordinarily be instantaneous and consequently the operator will usually release the clutches as soon as the lifting sectors strike the stops 178, but if it is desired to hold the pan momentarily in its extreme dumping position, as for dumping clay or other sticky material, such can be effected by properly slipping the clutches

slightly, or the pan can be vibrated back and forth in its dumping position by alternately engaging and releasing the clutches. Even if the clutches are held in firm gripping engagement after the lifters 56 strike the stops 178, there is no damage as this only results in slipping the wheels 20 over the ground.

Referring now to the draft bar mechanism 58, these draft bars are duplicated at opposite sides of the pan, with each bar pivoted to the forward lower portion of the pan on a pivot stud 184 projecting outwardly from the reinforcing plate 68. As shown in Figure 2, the two bars converge forwardly and have their front ends extending forwardly in parallelism. These parallel front portions are cross connected by a pin 186 which is adapted to swing upwardly into the box-like space between the parallel front portions 21a of the frame channels. The intervening length of said pin between the two draft bars 58 is adapted to engage with a draft hook 188 which has pivotal mounting on a cross shaft 189 supported in the frame channel portions 21a. The pin 186 and hook 188 constitute cooperating latching parts of a releasable draft latch which transmits draft from the forward portion of the frame to the pan. In the embodiment described, when the pan is in its digging position and when it is in its transport position the pin 186 remains in cooperative association with the draft hook 188, but preliminary to elevating the pan to its dumping position (Figure 5) said pin is released from the draft hook, whereby the draft bars 58 can swing backwardly for accommodating the tilting movement of the pan. In the embodiment illustrated in Figures 1 to 5 inclusive, the pin 186 and draft hook 188 are released from each other by the performance of a manual releasing operation, and in the embodiment illustrated in Figure 13 the releasing operation is effected automatically by the movement of the pan. Referring first to the embodiment of Figures 1 to 5 inclusive, the path of swinging motion of the pin 186 is defined by two parallel supporting links 191 which, at their forward swinging ends, have lateral bosses 191' in which the pin 186 is mounted. The upper ends of these spaced links are mounted on a transverse pivot rod 192 which has its ends supported in brackets 193 secured to the frame channels, suitable spacing sleeves being mounted on the rod 192 to maintain appropriate spacing between the links 191 and between said links and the brackets 193, as clearly shown in Figure 2. A foot pedal 195 is pivotally mounted at 196 on a short standard 197 rising from the cross plate 22. The portion of the pedal adapted to be depressed by the operator's foot extends rearwardly and downwardly under the transverse pivot rod 192, and is adapted to be held elevated against the under side of this rod by a tension spring 198 extending between the pivot standard 197 and a lug projecting from the pedal lever. The other end of said lever carries a pivot bolt 199 which engages in a slot 201 in the upper portion of a tripping link 202, the lower portion of which link is pivoted at 203 to the draft hook 188. The draft hook is normally held in a depressed position latching over the pin 186 by gravity and by a tension spring 204 which extends between a lug 205 on the draft hook and a forward point of fixed attachment on the frame. An extension tail 205 may be provided on the draft hook for engaging the under side of the plate 22 to limit the downward motion of the draft hook. When the draft

bars 58 are to be released in order to permit the pan to be tilted up to its dumping position, the pedal 195 is depressed, as shown in Figure 5, thereby operating through the link 202 to raise 5 the draft hook and separate the latching shoulder 188a of said hook from the pin 186. The pin 186 is prevented from moving upwardly with the hook in this releasing operation by the provision of two arcuate stops 206 projecting inwardly from the front portions 21a of the frame 10 in position to be engaged by the bosses 191 on the links 191 for limiting upward and forward movement of the pin 186. The slot 201 in the link 202 permits the hook 188 to move upwardly 15 in the relatching operation without causing movement of the lever or pedal 195. When the hook 188 is to be tripped through a remote control rope or cable, this rope is fastened directly to the hook and the pedal 195 and link 202 are 20 preferably removed.

When the empty pan swings down from its dumping position back to its transport position it is desirable to cushion or retard such return movement so that the stopping of the pan in 25 transport position will not cause shock or racking of the mechanism. Accordingly, we have provided a hydraulic dash-pot 208 which is operatively connected between the links 191 and a point of attachment on the frame. The rear end 30 of the dash-pot cylinder is pivotally connected at 209 (Figure 5) between a pair of lugs 211 (Figure 6) projecting forwardly from the transverse bracing tube 36. A piston rod 212 extends from the head end of the cylinder and is pivotally connected to a bolt 214 extending between the parallel links 191. The piston rod 212 is attached to a piston within the cylinder, which piston has either a forwardly facing cup washer of rubber or leather, or any suitable check valve embodied 35 40 within the piston and arranged whereby the piston can move rearwardly in the cylinder unimpeded, but when the piston is compelled to move forwardly by the lowering movement of the pan from dumping position the oil in the cylinder is trapped in front of the piston and has a restricted egress through or around the piston 45 for checking the downward movement of the pan.

Referring now to the two guiding or controlling links 59 at opposite sides of the pan, it will 50 be seen from Figures 3 and 8 that the forward end of each link is provided with a bearing hub portion 218 which is rotatably mounted on the collar 63 encircling the axle 44, this hub portion 55 being confined laterally between the axle bearing 45 and the lifting arm 56. Said hub 218 is preferably divided into two halves which are bolted together over the collar 63, in order to facilitate assembling the guide links over the 60 axle collar. The rear portion of each link 59 is bent downward slightly and at the end is provided with a slot 221 extending substantially lengthwise of the link. Engaging in this slot is a stud 222 which has an outer head or washer 65 223 engaging over the outer side of the link 59 for holding the link on the stud. The stud is secured to a bracket 224 which is riveted or otherwise rigidly secured to the side wall of the pan. Preferably, the inner end of the link 59 has 70 pivotal mounting on the frame on an axis concentric with the axis of the lifter 56, such being established by the pivotal mounting of said link around the axle collar 63, but the arrangement is not essentially limited to such concentric 75 mounting. The slot 221 establishes a lost motion

relation in the controlling connection 59 extending between this inner pivotal axis 44 on the frame and the outer pivotal axis 222 on the pan, but such lost motion relation might be established between the inner end of the link and the axis 44 or it might be made to occur within the body of the link. As hereinafter described, when the pan is in digging position the control link 59 is operative to function as a compression member and when the pan is in transport position this link is operative to function as a tension member.

Figures 3A, 3B and 3C diagrammatically illustrate the cooperation of the parts 51, 58, 59 and 61 in governing the movement of the pan from 15 digging position to transport position and in governing the relation of the pan in these positions. When the pan is lowered to digging position, as illustrated in Figures 3 and 3A, the engagement of the runners 54 against the bottom of the cut 20 retains the forward edge of the pan inclined downwardly at the most efficient digging or scooping angle. At this time the draft forces are transmitted through the two draft links 58, and the rear end of the pan is prevented from tilting 25 upwardly by the two guide links 59. With reference to this function of said guide links, it will be evident that in the forward motion of the implement a large force is acting against the forward cutting edge of the pan, as indicated by 30 the directional arrow F. Since the draft force is applied to the pivot 184 at a point above the point of application of the reversely acting force F, it will be evident that a rotative couple is created in the pan tending to swing its rear end 35 upwardly around the draft pivot 184 as a center. The direction of this rotative force is diagrammatically indicated in Figure 3A by the arc A passing through the pivot stud 222. At this time each pivot stud 222 is at the inner end of the 40 slot 221 of its guide link 59. Therefore, since the link 59 and stud 222 can at this time only swing upwardly about the arc B, concentric with the axle 44, the rotative tendency represented by the arc A merely forces the stud 222 against 45 the inner end of the slot 221 and establishes a compression stress in the link 59, whereby the link holds the rear end of the pan against tipping upwardly under the action of the force F.

Referring now to Figures 3B and 3C, when the 50 lifting mechanism is actuated the lifting links 51 apply a force acting upwardly and rearwardly on the lifting pivots 67. This lifting force is applied to the pan intermediate the link pivots 184 and 222 but closer to the front end of the pan, 55 and such lifting force has a rearward component along the line between the pivots 67 and 69. The first action of this lifting force is to swing the front end of the pan upwardly around the rear ends of the runners 54, which remain in sliding 60 contact with the ground during this initial lift, owing to the fact that the preponderance of the weight of the pan and the load therein is behind the point of application of the lifting force at the pivots 67. This initial upward tilting of the 65 front end of the pan serves the advantageous purpose of settling the load back into the rear portion of the pan. During this initial lifting movement a draft load is continuously maintained on the draft links 58 by reason of the drag of the runners 54 on the ground and by reason of the slight rearward component in the lifting force exerted on the pivots 67. The upward lifting of the front end of the pan ceases as a 70 tilting motion as soon as the studs 222 engage the 75

rear ends of the slots 221, and thereafter the upward movement of the pan is one of direct lift. The relative movement between the studs 222 and slots 221, which causes the studs to engage the rear ends of the slots, comes about by reason of the weight of the load in the pan tending to swing the pan counterclockwise with respect to the pivot centers 67 and 69, and also by reason of the slight movement which the draft pivots 184 5 can have in a rearward direction in moving upwardly along the arc C. The parts are so proportioned that the studs 222 engage the rear ends of the slots 221 when the draft pivots 184 are still a considerable distance below a straight line 10 extending between the points 186 and 222, as indicated by the dash and dot lines in Figure 3B. While the pan was in digging position with the force F acting against its cutting edge, the draft links 58 were in tension and the guide links 59 15 were in compression. As soon, however, as the studs 222 engage the rear ends of the slots 221, in the above described direct lifting movement of the pan, this relation of forces is reversed, i. e., a compression force is established in the draft links 58 and a tension force is established in the guide links 59.

It will therefore be seen that approximately as soon as the studs 222 move backwardly and engage the rear ends of the slots 221 in the upward 30 tilting of the front end of the pan, the lifting movement thereafter transmitted to the pan compels the latter to move upwardly with a bodily shifting or translatory motion of the pan. When the pan reaches its final position for transport 35 the draft links 58 and guide links 59 are in approximately the positions illustrated in Figures 3C and 4. The clutches are released as soon as the toggle locks 77-78 snap into locked position, and thereupon the pan is held in its transport 40 position by the toggles. Any continued engagement of the clutches after the pan reaches transport position cannot accidentally dump the pan but merely exerts increased pull on the draft links 58, owing to pressure engagement between 45 the curved portions 57a of the lifting links 57 and the curved surfaces 62 of the axle collars 63 tending to rotate the pan, but since the draft links 58 are still latched to the frame this continued engagement of the clutches only results in slipping 50 of the wheels 20.

When it is desired to dump the pan the pedal 195 is first actuated to lift the draft hook 188 out of engagement with the pin 186, and thereafter the clutches are again engaged by pulling the 55 control lever 101 forwardly with a relatively slow, steady movement for producing corresponding motion of the sector plate 107. The releasing of the draft bars 58 permits them to swing backwardly as the pan swings upwardly to the position 60 illustrated in Figure 5. As previously remarked, the pan may be held in this upended dumping position by properly slipping the clutches, and is quickly returned to transport position when the clutches are released. This return movement of 65 the pan from dumping position to transport position is cushioned by the retarding action of the cushion cylinder or dash pot 208, as previously described. During the time that the pan is moving up toward and down away from dumping position the pins 86 at the rear ends of the toggle locks are riding idly over the outer track portion 70 of each lifting arm 56, and when the pan is fully returned to transport position these pins engage in the hooks 75 of the lifting arms for holding 75 the pan in transport position. At the same time,

the draft links 58, in swinging forwardly, restore the pin 186 into latched engagement with the draft hook 188. When it is now desired to drop the pan to digging position, the control lever 101 is given a quick forward jerk, whereby it is freed 5 from the sector 107, and thereafter continued forward movement of said lever operates through the arms 125 to release the toggle locks 77-78 for permitting the pan to drop down to digging 10 position.

It will be seen that in the embodiment hereinbefore described all control operations are performed simply by the manipulation of the control lever 101 and the draft tripping pedal 195. Both of these are conveniently accessible to an operator standing on the operator's platform 37. If it is desired to have the tractor driver actuate these controls from his seat on the tractor, such can be easily provided for by the arrangement of control connections illustrated in full lines in Figure 4. In this arrangement, a suitable standard 231 is erected at the front end of the frame, having a bracing attachment 232, and comprising parallel bars between the upper ends of which are mounted suitable rollers 233. A pull line 236 is extended over one of these rollers and down to a suitable point of attachment on the latching hook 188, and where all operations of the machine are to be by remote control the foot pedal 195 and link 202 30 may be removed. Another pull line 237 is extended over another roller 233 and brought back for attachment to the upper end of the control lever 101. The pulling of these cables 236-237 by the operator from his seat on the tractor 35 serves to perform the same control operations previously described. When two or more scraping implements are connected together in tandem behind a tractor they may all be controlled by the tractor driver, or by an operator standing 40 on the platform of the front scraper. As illustrative of this arrangement, we have shown in dotted lines in Figure 4 a supporting standard 231' which is substantially a duplicate of the standard 231 and which may be mounted on the 45 front implement at the rear of the operator's platform for supporting pull lines extending back to the control devices of the rear implement. The rear implement would preferably have a standard 231 mounted at its forward end, as illustrated in full lines in Figure 4, for guiding the control cables to the tripping pedal and to the control lever. When operating a plurality of implements in tandem the control connections 50 may be arranged for simultaneous raising and dropping of all of the pans, or they may be arranged for selective raising and dropping of the 55 pans of the different implements.

Figures 10 and 11 illustrate a modified construction of clutch mechanism 72. In this embodiment, the clutch actuating arm 148a is mounted on a shaft 163a which is rotatably supported in the driven clutch element 156, in the same manner as described of the embodiment of Figures 8 and 9, but the inner end of this shaft 65 163a carries, in lieu of the cam 164, an arm 164a carrying a roller 164b. When the arm 148a is swung outwardly to its clutch engaging position the roller 164b is pressed outwardly against the inner side of an arcuate plate 165a which is set 70 cured to the inner side of the clutch band 159 at a point adjacent to one end thereof. The resulting outward pressure of the clutch band against the flange 155 of the driving clutch element 75 causes this end of the band to rotate with said 75

flange (in the direction of the arrow) and thereby causes the entire band to expand outwardly against said flange, whereupon the driven clutch element rotates with the driving clutch element.

5 The length of the arcuate plate 165a is sufficient to remain in contact with the roller 164b in the slight angular movement of the band relatively to the driven clutch element as the band is expanded outwardly against the flange 155. If desired, an adjusting screw 174 (such as shown in Figure 9) may be provided to coact with the link 167a for adjusting the clutching action of the band. In the ordinary use of the implement the pan will be raised to transport position (Figure 4) or to dumping position (Figure 5) while the implement is traveling forwardly in a substantially straight line path, and at this time the two clutch mechanisms at opposite sides of the pan will transmit the same rate of rotative movement from their respective wheels to the axle 44. However, the operations of lifting the pan to transport position or of lifting the pan to dumping position, can also be effected while the implement is traveling through a sharp curve, or even if the implement is being swiveled on one wheel, with this inner wheel remaining stationary or even rotating backwardly. This is because the above described clutch mechanism of Figures 10 and 11 is only operative to exert effective clutching engagement between the driving and driven clutch elements when the wheel and drum 154 of that clutch mechanism are rotating forwardly, owing to the inherent snubbing action of this type of clutch mechanism. When the driving clutch element is standing stationary or rotating backwardly the clutch mechanism is substantially ineffective to establish a gripping pressure between the clutch band and the drum 154.

Another modified construction is illustrated in Figure 12. In this embodiment equal clutching or braking action is obtained for either direction of rotation. The actuating lever 148a operates an arm 164a carrying a roller 164b which is adapted to bear outwardly against an arcuate plate 165a mounted on the inner side of the band 159, in substantially the same manner as described of Figures 10 and 11. In this embodiment, however, the arcuate plate 165a is secured to an intermediate portion of the band 159, and both ends of the band are pivotally connected to links 167b which have their inner ends mounted on pivots 171b. Springs 176b are connected to the links 167b or to the ends of the band for normally holding the latter in non-clutching relation. It will be evident that irrespective of the direction of rotation of the driving clutch element, when the roller arm 164a causes outward pressure on the plate segment 165a a snubbing action will occur between that point of the band and the end of the band extending in the direction of rotative movement. If desired, an adjusting screw or screws 174 (Figure 9) may be arranged to cooperate with one or both of the link pivots 171b for adjusting the gripping action of the band.

In each of the preceding embodiments, the expansion of the ring segments 142, 142 may be such as to establish a truly arcuate track for the roller end of the clutch actuating lever 148, 148a, which track will be substantially concentric with the clutch axis for the purpose of maintaining the clutch actuating lever in its position of maximum clutch engagement. On the other hand, the ring segments 142, 142 may only be expanded part way, or their expansion may be contracted

after an initial complete expansion, for obtaining a partial or slipping engagement of the clutch at any point in the rotative movement of the driven clutch element.

In Figure 13 we have illustrated a modified embodiment of latching connection between the front end of the draft link and the frame, which latching connection is automatically released when the pan is lifted from digging position to transport position, thereby avoiding the necessity of manually actuating a tripping pedal, such as the pedal 195 in the preceding embodiment. In this modified embodiment, the supporting links 191a are pivotally connected to the draft links 58 at points spaced rearwardly from the 15 cooperating latch portions. That is to say, the latching portion on the draft links is represented by the transverse pin or spacing sleeve 186 at the front ends of said draft links, and the supporting links 191a are pivotally connected with 20 the draft links on a transverse pivot pin 191b which is spaced rearwardly from the latching portion 186. The upper ends of said supporting links 191a are pivotally connected at 192a to a supporting bracket structure 193a, in much the 25 same manner as described of the preceding embodiment. The piston rod 212 of the cushioning cylinder 208 is also operatively connected at 214 to these supporting links 191a. The latching hook 188 is also pivotally mounted on a heavy trans- 30 verse pin 189 extending between the closely spaced front portions of the frame channels. A stop lug 205a at the forward end of said hook is adapted to engage an adjustable stop consisting of a set screw 238 which threads down through a 35 tapped boss on the plate 22 and which has a lock nut 239 for securing said set screw in any adjusted position. If desired, a suitable spring, like the spring 204 of Figure 3, may be operatively connected with the latch hook, normally tending to 40 swing said hook downwardly. The nose portion of the latching hook has a protruding V-shaped edge 188b which, when it is below the medial thrust line passing through the latching collar 186, tends to cam this collar upwardly into the 45 recessed portion of the hook upon rearward pull being exerted on the draft links, and which, when it is above this medial thrust line, tends to cam this collar 186 downwardly out of engagement with the hook. When the pan is down in its 50 digging position the draft links 58 assume approximately the angularity illustrated in the dotted line position in Figure 13. This places the latch portion 186 of the draft links within the embrace of the latching hook. As the pan is 55 raised from digging position up to transport position the rear ends of the draft links swing upwardly therewith, and when the pan has arrived in transport position, or is just approaching this position, the draft links assume the more nearly 60 horizontal position approximately illustrated in full lines in Figure 13. This causes the latching portion 186 to be swung downwardly to the point where the medial thrust line through this latching portion is disposed below the edge 188b of 65 the latching hook. Thereupon, when the pan is 70 swung up to dumping position the draft bars 58 are free to swing backwardly with the pan. By appropriately adjusting the set screw 238, the point at which the two latch members 186 and 188 are free to release automatically can be adjusted to occur just at the time the pan reaches transport position, or at any earlier point in the upward movement of the pan from digging position to transport position. Arcuate stops 206a, 75

similar to the stops 206 of the preceding embodiment, cooperate with the lateral bosses 191 on the links 191a for limiting upward and forward movement of the pivot pin 191b. With the movement of the pan from digging position up into transport position, the clutches are released just as soon as the pan arrives in transport position and the toggle locks have snapped into locking position. It will be evident that the above described automatically releasing latching arrangement, in dispensing with the manual control necessary in the case of the tripping pedal 195, greatly simplifies the operation of the implement. It will be understood that, if desired, the point of latch release may be made to occur between the draft links 58 and the pan, in either a manually operated embodiment or an automatically operated embodiment.

Referring to Figures 2, 3, and 4, it is desirable to provide curved guides 241, mounted fixedly on the inner sides of the frame channels 21 for cooperation with the lifting pivots 67 in those constructions wherein a checking or cushioning cylinder, such as the cylinder 208, is arranged to exert its checking force on the pan through the draft connections. These curved guides are shown as consisting of curved sections of angle bar having their longitudinal flanges riveted to the web portions of the frame channels and having their curved transverse flanges projecting inwardly to a sufficient depth where they can be engaged by the lifting pivots 67. The lifting pivot studs 67 have rollers or projecting portions 67a (Fig. 17) which extend outwardly a sufficient distance so as to be able to engage the guides. The draft pivots 184 and draft links 58 lie considerably closer to the sides of the pan, so that they are not in the fore and aft plane of said guides. The rollers or end portions 67a of the pivot studs 67 bear against these curved guides 241 as the pan swings down from dumping position to transport position. Thus, notwithstanding the checking action which the cushioning cylinder 208 is opposing to forward movement of the draft links 58, these curved guides compel said return movement of the pan to occur rotatively substantially around the axle center and to occur substantially concurrently with the return motion of the axle so that the pan and links will resume the proper transport positions illustrated in Figure 4. If desired, the guides 241 may be provided with the upwardly and forwardly inclined deflecting surfaces 242 at their forward ends, to aid in restoring the parts to their proper positions in the event that the draft connection should become accidentally released while the pan is moving forwardly in digging position.

In Figures 14, 15 and 16 we have illustrated a modified arrangement of the clutch actuating connections whereby there is always assured the transmission of equalized operating effort to both clutches. The two toggle tripping sleeves 105, 105 have their inner ends secured to the upwardly extending spaced arms 106, which arms have their upper ends joining into the control lever 101, in substantially the same relation illustrated in Figure 6, except that the lower arm portions 106 are spaced further apart to accommodate the equalizing connections. Suitable bearing brackets 245 are secured to the frame or operator's platform so as to provide bearing support for the inner ends of said sleeves. In this modified embodiment, instead of having a single shaft 102 extending from side to side of the machine for operating both clutch actuating arms 104, there

are provided two of these shafts 102, one individual to each arm 104, the inner ends of said shafts having independently rotatable bearing mounting in a boss 107a formed as an integral part of the sector plate 107. To each side of this boss 107a are hubs 247 which are fixedly secured to their respective shafts 102 by set screws or keys 248. Arms 249, 249 extend upwardly from the hubs 247 between the outer arms 106. The upper ends of said arms 249 are apertured to receive bolts or links 251 which have yoke-shaped extremities 251a at their forward ends. The rear ends of said bolts or links are threaded for the reception of nuts 252 bearing against the back sides of the arms 249, by the manipulation of which nuts the effective lengths of the links 251 can be adjusted for individually adjusting the engagement of the clutches. The yoke shaped extremities of said links embrace the ends of an equalizing bar 254, being pivotally connected to the ends of said bar 20 by pivots 255. The center of said equalizing bar 254 is pivotally connected by a pin 256 between two vertically spaced ears 257 projecting forwardly from the sector plate 107. The mounting and the operation of the inertia responsive latch 108 are substantially the same as previously described.

When the lever 101 is jerked forward quickly, preparatory to releasing the locking toggles, the operation is the same as described of the preceding embodiment, the inertia responsive latch 108 rising to clear the shoulder 109 on the sector plate 107, and continued motion of the lever 101 serving to rotate the sleeves 105 independently of the shafts 102. When the lever is drawn forward relatively slowly, however, for causing engagement of the clutches, the latch 108 engages the shoulder 109 and results in the sector plate 107 moving correspondingly with the lever. The rocking mounting of the equalizing bar 254 on the plate or arm 107 causes an equalized pressure to be transmitted through the links 251 and arms 249 to the two shafts 102, whereby any tendency of one clutch to engage ahead of or to the exclusion of the other is prevented. The plate or arm 107 has the previously described cross bar 115 at its rear edge for engaging the rear sides of the arms 106, so that this plate or arm is restored to normal position when the control lever 101 is returned to normal position. As previously described, it is the action of the tension springs 119 exerting pressure through the arms 118 and sleeves 105 that restores the lever 101 to normal position when forward pulling effort on the lever is released.

In Figures 17, 18, 19 and 20 we have illustrated how an improved arrangement of end gate may be employed on our wheeled scraper for better retaining the load in the pan during transport. The gate, designated 264 in its entirety, comprises a transverse plate 265 having its upper and lower margins bent laterally to form the stiffening flanges 265a and 265b. Spaced inwardly from the ends or sides of said plate are two vertical angle bars 266, each of which has one of its flanges secured to said plate 265. Forwardly extending supporting arms 267 are fastened to the other flange of each angle bar, and the front ends of said arms 267 are apertured to receive pivot pins or bolts 268. These pivot members extend between pairs of depending pivot plugs 269 extending downwardly from the under side of the transverse bracing tube 36. It will be noted from Figures 18 and 19 that the lower edge of each gate supporting arm 267 is inclined upwardly and for-

wardly, and rigidly secured along this inclined edge of each arm is a plate 271. As will be later described, these two plates, one under each arm 267, are engaged by the pile of earth entering the front end of the pan in the digging operation, whereby the gate is raised to a non-obstructing position.

Figure 18 shows the gate in its normal closed position for substantially closing the open front end of the pan when the pan is in transport position. The gate is retained in this position by two short arms or brackets 272, which are rigidly secured at the outer upper corners of the plate 265 and which extend forwardly for resting on the corners of the horizontal plates 38a extending rearwardly from the side portions of the operator's platform. In the preferred construction the gate is spaced slightly from the side walls and from the bottom wall of the pan when the pan is in transport position, there being no necessity of actual contact between the gate and the pan to hold the load in the pan, although such contact or approximate contact can be provided for in the construction if desired. All of the remaining parts of the machine, including the pan and its several link connections, are the same as previously described. When the pan is swung downwardly to digging position its side walls pass slightly beyond and overlap the side edges of the gate. As shown in Figure 20, with the pan moving forwardly in digging position, a slope or rise of earth E accumulates in front of the pan and this sloping rise of earth reacts upwardly against the inclined runner plates 271 on the bottoms of the arms 267, whereby the gate is automatically raised to a clear position, out of the path of the soil entering the pan. When the pan and its load are swung upwardly to transport position, the pan moves rearwardly, as previously described, so that when the pan arrives in its transport position, illustrated in Figure 18, the gate 264 substantially closes the front end of the pan. If any rocks, or other portions of the load project forwardly from the pan in position to strike the lower edge of the gate, the gate is free to rise therewith until this projecting portion of the load is shaken off or is moved back into the pan, whereupon the gate resumes its normal closing position. If desired, the runner plates 271 may be utilized to raise the gate when the pan is tilted upwardly to dumping position, as we shall now describe.

Referring to Figure 17, when the pan is in its transport and digging positions, and is moving between these positions, the parallel rear portions 58c of the draft links 58 are substantially in the transverse plane of the gate, but since these rear portions are spaced outwardly beyond the sides of the gate they transmit no movement thereto. When the pan is tilted upwardly to its dumping position (Figure 19), the rearward movement of the draft links 58 brings the diagonal portions 58b of these two links into contact with the sloping plates 271 secured to the under sides of the gate supporting arms 267, as indicated in dotted lines in Figure 17 and in full lines in Figure 19. Hence, during this dumping movement of the pan, the gate is cammed upwardly by the diagonal portions 58b of the draft links 58 to a raised position, approximately as shown in Figure 19, in order to permit of a more rapid dumping of the contents of the pan. When the pan is swung back to its transport position after dumping, the gate drops back to its normal po-

sition with the stop arms 272 resting on the stationary side plates 38a.

In Figures 21 and 22 we have disclosed an improved construction of mechanism for checking or controlling the movement of the pan from dumping position back to transport position. In its preferred embodiment this controlling mechanism is in the form of a hydraulic cylinder 208', somewhat similar to the previously described hydraulic cushioning cylinder 208. The action is similar to that of the cylinder 208 in that the downward swing of the pan is cushioned, but the cylinder 208' has the additional feature of holding the pan upended in its dumping position for a considerable time interval, before allowing the pan to swing down through the remaining part of its travel. The advantage of such operation is that the operator only needs to engage the clutches for a sufficient time to bring the pan up to dumping position, whereupon the clutches can be released, after which the pan is automatically controlled so as to remain in this elevated dumping position for a considerable time interval before it starts back to transport position.

The two main relatively movable parts of this construction comprise the cylinder 208' and a piston 281 therein. The piston is secured to a piston rod 282 which extends out through a guide boss 283 formed on an end head 284 which closes one end of the cylinder. Two packing washers 283a are pressed inwardly by coil springs 283b against the rod 282. The head 285 closing the other end of the cylinder has any suitable attachment or mounting means thereon, such as a pair 35 of spaced lugs 286 projecting therefrom for receiving a pivot bolt 287.

The cylinder is operatively connected between the movable supporting links 191a and the transverse bracing tube 36. In the arrangement illustrated, the piston rod 282 is extended rearwardly through vertical slots 288 provided in the front and rear walls of said tube, and the rear end of said piston rod is pivotally connected at 289 to lugs 291 projecting from the rear side of the tube. The pivot bolt 287 extending between the apertured lugs at the other end of the cylinder has pivotal attachment to the supporting links 191a. By connecting the piston rod 282 to the back side of the bracing tube 36, a longer length of cylinder can be employed within the available space, and a stronger attachment for the piston rod is obtained, although, if desired, this arrangement might be reversed by connecting the cylinder 208' to the bracing tube 36 and by connecting the piston rod 282 to the links 191a. Also, while we have shown this improved form of checking cylinder 208' as being connected with the automatically releasing type of draft connection disclosed in Figure 13, it will be understood that such checking cylinder may be used with equal advantage in association with the manually released type of draft connection illustrated in Figures 3, 4 and 5.

Referring now to the checking mechanism within the cylinder, a cup washer 292, of leather, rubber, or the like, is clamped between the piston 281 and a plate 293. The plate 293, cup washer 292, and piston 281 are clamped together against a shoulder 282' on the piston rod, by a nut 294 screwing over a reduced threaded end 70 of said rod.

The cylinder is substantially filled with oil and when the cylinder travels to the left this oil can pass rather freely around the piston 281 and past the cup washer 292 into the left hand end of the

cylinder, whereas when the cylinder travels toward the right the cup washer greatly restricts the flow of oil into the right hand end of the cylinder. When the pan is elevated to its full dumping position the parts are approximately in the relation illustrated in full lines in Figure 22, and the weight of the pan is tending to pull the cylinder to the right. A primary by-pass 295 is so arranged that it is ineffective to by-pass oil from one side of the piston to the other at this time, only becoming effective after the cylinder has moved to the right through a predetermined distance. One of the novel features of the construction is that this by-pass 295 is carried by the piston 281, and hence there are no ports or openings in the walls of the cylinder into which the cup washer 292 might be jammed and cut. Said by-pass 295 is incorporated in a piston valve plunger 296 which is slidably mounted in the piston 281. A guide boss or bracket 297 may project from the front side of the piston to afford a greater length of guiding support for the plunger 296. A head 298 on the apertured end of the plunger is adapted to abut the plate 293 for limiting the movement of the plunger through the piston in one direction. The by-pass 295 extends lengthwise through the plunger for a sufficient distance to establish by-pass communication from one side of the piston to the other when this head 298 is engaging the plate 293. For clarity of illustration, two different positions of the piston have been illustrated in dotted lines, such as would correspond to a reciprocatory piston, but it will be understood that when the device is mounted as illustrated in Figure 21 it is the cylinder that moves, rather than the piston.

As previously remarked, when the pan is in its full dumping position, the checking cylinder parts are in the relation illustrated in full lines. At this time, the oil trapped in the left hand end of the cylinder has a very restricted flow to the right hand end of the cylinder, as by leakage around the cup washer 292 and along the surface of the plunger 296. Hence, the pan is held in its dumping position for a considerable time, notwithstanding the fact that the clutches have been released. As the cylinder gradually moves toward the right the oil pressure exerted against the left hand end of the plunger 296 holds the right hand end thereof pressed up against the cylinder head 285, so that the plunger follows this gradual movement of the cylinder. As soon as the lateral branch of the by-pass 295 passes beyond the piston 281 and boss 297, a more rapid rate of flow of the oil into the right hand end of the cylinder occurs. Thereafter the pan moves downwardly with a more rapid movement, into its transport position, the restriction afforded by the by-pass 295 being sufficient, however, to cushion this more rapid movement of the pan so that there will be no shock transmitted to the parts. When the pan is again elevated to dumping position the cylinder head 285 engages the right hand end of the plunger 296 and restores it to the full line position illustrated, in which position it is again ready to control the movement of the pan.

While we have disclosed what we regard to be the preferred embodiment of our invention, nevertheless it will be understood that such embodiment is merely exemplary and that numerous modifications and rearrangements may be made therein without departing from the essence of the invention.

We claim:

1. In a scraper, the combination of a frame, ground engaging members supporting said frame, a pan, mechanism for raising said pan from digging position to transport position and from transport position to an upended dumping position out of contact with the ground for dumping from the front end of said pan, said mechanism comprising a power driven lifting member, a lifting connection between said lifting member and said pan for raising said pan from digging position to transport position, a releasable draft connection between said pan and said frame, and control means connected between said frame and said pan for holding the latter in proper digging position. 5

2. In a scraper, the combination of a frame, ground engaging members supporting said frame, a pan, mechanism for raising said pan from digging position to transport position and from transport position to an upended dumping position for dumping from the front end of said pan, said mechanism comprising a lifting member deriving power from the traction energy of one of said ground engaging members, a lifting connection between said lifting member and said pan, said lifting member and lifting connection enabling said pan to lower to digging position by gravity and operative to raise said pan to transport position by power, a releasable draft connection between said pan and said frame, and a control link pivotally connected between said pan and said frame for resisting the tendency of the rear portion of said pan to turn upwardly in the digging operation. 35

3. In a scraper, the combination of a frame, wheels supporting said frame, a pan, mechanism for raising said pan from digging position to transport position and from transport position to an upended dumping position for dumping from the front end of said pan, said mechanism comprising a lifting member deriving traction power from one of said wheels, a lifting connection between said lifting member and said pan enabling said pan to lower by gravity to digging position and operative to raise said pan from digging position to transport position by power, a releasable draft connection between said pan and said frame, and control means operatively connected between said pan and said frame comprising a link operating under compression when said pan is in digging position and operating under tension when said pan is in transport position. 45

4. In a scraper, the combination of a frame, ground engaging members supporting said frame, a pan, a pair of links pivotally connected with said pan at longitudinally spaced points of said pan, means pivotally connecting other portions of said links with said frame at longitudinally spaced points of said frame, and power driven mechanism for raising said pan from digging position to transport position and for moving said pan from transport position to an upended dumping position out of contact with the ground, 65 one of said links being releasable for enabling said pan to be moved from transport position to dumping position. 55

5. In a scraper, the combination of a frame, ground engaging members supporting said frame, a pan, a pair of links operatively connected with said frame, means pivotally connecting one of said links with the forward portion of said pan, means pivotally connecting the other of said links with the rearward portion of said pan, and lift- 70 75

ing mechanism comprising a lifting member operatively connected with said pan and including means deriving lifting power from one of said ground engaging members.

5. 6. In a scraper, the combination of a frame, ground engaging members supporting said frame, a pan, a power driven lifting member having rotatable mounting on said frame, a lifting connection between said lifting member and said pan, a draft link operatively connected between said pan and the forward portion of said frame, and a control link operatively connected at one end with said pan and pivotally mounted at its other end on said frame for rotative movement 15 about a relatively stationary axis substantially coincident with the axis of said lifting member.

7. In a scraper, the combination of a frame, ground engaging members supporting said frame, a pan, a lifter member mounted on said frame for rotation about a fixed axis, a lifting connection between said lifter and said pan, draft mechanism operatively connected between said pan and the forward portion of said frame, a guide member on said pan, and a link having a lost motion connection between said lifter axis and said guide member.

8. In a scraper, the combination of a frame, ground engaging members supporting said frame, a pan, a draft connection between said pan and said frame, a lifting member rotatably mounted on said frame, a lifting connection between said lifting member and said pan operative by rotation of said lifting member in one direction to raise said pan from digging position to transport position, and releasable locking means mounted on said frame for holding said lifting member against rotation in the reverse direction independently of said draft connection.

9. In a scraper, the combination of a frame, ground engaging members supporting said frame, a pan, a link connection between said pan and said frame, a rotatable lifting member mounted on said frame, a lifting connection between said member and said pan, means for transmitting rotative movement to said lifting member whereby in one direction of rotation of said lifting member it is operative to raise said pan from digging position to transport position and then to tilt said pan to dumping position, and releasable toggle lock mechanism mounted on said frame and engageable with a shoulder on said lifting member for preventing reverse rotation of said lifting member when the pan is in transport position.

55. 10. In a scraper, the combination of a frame, ground engaging members supporting said frame, a pan, lifting mechanism for raising said pan from digging position to transport position and from transport position to upended dumping position, clutch mechanism for controlling the transmission of power to said lifting mechanism, releasable locking mechanism for holding the pan when raised to transport position, and a single control member operative to actuate said clutch mechanism and said locking mechanism, one independently of the other.

11. In a scraper, the combination of a frame, wheels supporting said frame, a pan, lifting mechanism for raising said pan from digging position to transport position and from transport position to upended dumping position, clutch mechanism for transmitting traction power from one of said wheels to said lifting mechanism, releasable locking means for holding said pan after it has been elevated to transport position, oper-

ating connections for said clutch mechanism and operating connections for said locking mechanism, and a single control member actuatable to transmit actuating motion selectively to either of said operating connections.

5. 12. In a scraper, the combination of a frame, ground engaging members supporting said frame, a pan, lifting mechanism for raising said pan from digging position to transport position and from transport position to dumping position, a draft link pivotally connected with said pan and extending forwardly therefrom, a supporting link pivotally connected to the forward portion of said draft link and pivotally connected with said frame, and releasable latching devices associated 15 with said draft link and with said frame.

13. In a scraper, the combination of a frame, ground engaging members supporting said frame, a pan, power operative lifting mechanism for raising said pan from digging position to transport position and from transport position to upended dumping position for dumping from the front end of said pan, clutch means deriving power from one of said ground engaging members for transmitting motion to said lifting mechanism, a draft link pivotally connected with said pan and extending forwardly therefrom, a supporting link pivotally connected with said draft link and with said frame, a draft latch movably mounted on said frame and adapted to engage 30 with a cooperating latch member on said draft link, and manually actuated means for releasing said latch.

14. In a scraper, the combination of a frame, ground engaging members supporting said frame, a pan, lifting mechanism for raising said pan from digging position to transport position and from transport position to dumping position, and automatically releasing draft mechanism operative to establish a draft connection between said pan and said frame when said pan is in digging position and operative to automatically disconnect said draft connection when said pan is moved into another one of its positions.

15. In a scraper, the combination of a frame, ground engaging members supporting said frame, a pan, lifting mechanism for raising said pan from digging position to transport position and from transport position to dumping position, a draft link connected with said pan, a supporting link pivotally connected between said draft link and said frame, and cooperating latching members on said frame and on said draft link operative to transmit draft to said pan when the latter is in its digging position but automatically 55 releasable by the change of angle of said draft link as said pan is elevated to its transport position.

16. In a scraper, the combination of a frame, ground engaging members supporting said frame, a pan, a cylindrical bearing surface mounted on said frame, lifting mechanism for raising said pan from digging position to transport position, said lifting mechanism comprising a member having an arcuate bearing surface adapted to engage 65 with the cylindrical bearing surface on said frame, said bearing surfaces being separated when said pan is in digging position, lifting mechanism for raising said pan from digging position to transport position, said bearing surfaces being brought 70 into contact when said pan is raised to transport position, said lifting mechanism being thereafter operable to rotate said pan about the axis of said cylindrical bearing surface to an upwardly extending dumping position, and a guide link 75

pivottally connected between said pan and said frame guiding the position and movement of said pan.

17. In a scraper, the combination of a frame, ground engaging members supporting said frame, a pan movable between digging, transporting and dumping positions, a power actuating member for moving said pan from one of said positions to another, a clutch for transmitting traction power from one of said ground engaging members to said power actuated member, said clutch comprising driving and driven clutch elements, a clutch actuating member pivottally mounted on said driven clutch element and movable directly therewith, said clutch actuating member having clutch releasing and clutch engaging positions relatively to said driven clutch element, and clutch control mechanism comprising a plurality of cooperating expansible and contractible ring segments adapted, when expanded, to form an arcuate track for holding said clutch actuating member in its clutch engaging position during the rotative movement of said driven clutch element.
18. In a scraper, the combination of a frame, ground engaging members supporting said frame, a pan having an open front end adapted to receive soil therethrough when said pan is lowered to digging position, lifting mechanism for raising said pan from digging position to transport position and from transport position to dumping position, means for driving said lifting mechanism from one of said ground engaging members, a gate supported on said scraper arranged to occupy a closed position adjacent to the open front end of said pan when said pan is raised to transport position, and automatically operating deflecting means extending diagonally forwardly from said gate, effective when said pan is in digging position, for causing said gate to assume a position not obstructing the entrance of soil into said pan.
19. In a scraper, the combination of a frame, ground engaging members supporting said frame, a pan having an open front end adapted to receive soil therethrough when said pan is lowered to digging position, lifting mechanism for raising said pan from digging position to transport position and from transport position to dumping position, a gate supported on said scraper arranged to occupy a closed position adjacent to the open front end of said pan when said pan is raised to transport position, and automatically operating means for shifting the position of said gate in an upward direction when said pan is moved upwardly toward dumping position, and effective when said pan is in digging position for causing said gate to assume a position not obstructing the entrance of soil into said pan.
20. In a scraper, the combination of a frame, ground engaging members supporting said frame, a load receiving pan, lifting mechanism for raising said pan from digging position to transport position and from transport position to dumping position, clutch means controlling the actuation of said lifting mechanism, and means operating independently of said clutch, means for automatically retaining said pan in effective dumping position for a considerable time interval.
21. In a scraper, the combination of a frame, ground engaging members supporting said frame, a load receiving pan, lifting mechanism for raising said pan from digging position to transport position and from transport position to dumping position, clutch mechanism for controlling the transmission of power to said lifting mechanism, and hydraulic control mechanism operatively connected with said pan and functioning to retain said pan in an effective dumping position for a considerable time interval and thereafter permitting lowering of said pan to transport position with a retarded motion independently of the engagement of said clutch mechanism.
22. In a scraper, the combination of a frame, ground engaging members supporting said frame, a load receiving pan, lifting mechanism for raising said pan from digging position to transport position and from transport position to dumping position, draft mechanism arranged to transmit draft force from said frame to said pan, and hydraulic control mechanism operatively connected between said draft mechanism and said frame for controlling the motion of said pan from dumping position back to transport position.
23. In a scraper, the combination of a frame, ground engaging members supporting said frame, a pan, draft means operatively connected between said pan and said frame, pan actuating mechanism operable to cause movement of said pan from digging position to transport position to dumping position and back to transport position while the scraper is moving continuously forwardly, the movement of said pan from transport position to dumping position occurring about an axis which is substantially stationary relative- 30. 25. 30. 35. 40. 45. 50. 55. 60. 65. 70. 75. 80. 85. 90. 95. 100. 105. 110. 115. 120. ground engaging members supporting said frame, a pan carried by said frame and movable between digging, transporting and dumping positions relatively to said frame, pan actuating mechanism operable to cause movement of said pan from digging position to transport position and from transport position to dumping position, lock mechanism operative in its locked condition to prevent said pan moving from transport position back to digging position, and means for releasing said lock mechanism independently of the operation of said pan actuating mechanism.

27. In a scraper, the combination of a frame, ground engaging members supporting said frame, a pan carried by said frame and movable between digging, transporting and dumping positions relatively to said frame, said pan being movable to digging position by gravity, power driven lifting mechanism operable to lift said pan from digging position to transport position and to move said pan from transport position to dumping position, one-way lock mechanism operative in its locked condition to prevent said pan moving from transport position back to digging position, but permitting said pan to be moved from transport position to dumping position, and means for releasing said lock mechanism independently of the operation of said lifting mechanism.

30 28. In a scraper, the combination of a frame, ground engaging members supporting said frame, a pan carried by said frame and movable between digging, transporting and dumping positions relatively to said frame, a lifter operatively connected with said pan for moving the pan between digging, transporting and dumping positions, and lock mechanism for holding said pan in transporting position, said lock mechanism comprising a shoulder moving with said lifter through a predetermined path, a stop member movable in the path of said shoulder, apparatus connected with said frame for holding said stop member at one point in said path whereby to prevent said shoulder from moving beyond said point in a lowering direction of said pan, but permitting said shoulder to move beyond said point in a lifting direction of said pan, and means for releasing said apparatus to permit movement of said stop member and of said shoulder in a direction from said point such as will permit lowering of said pan.

29. In a scraper, the combination of a frame, ground engaging members supporting said frame, a pan carried by said frame and movable between digging, transporting and dumping positions relatively to said frame, lifting mechanism for moving said pan from one of said positions to another, a driving member, a clutch operatively connecting said driving member with said lifting mechanism, said clutch comprising driving and driven clutch elements, a clutch operating device, and mechanism actuated by said device for causing clutch engagement of said driving and driven clutch elements when said operating device is moved to one position and for maintaining clutch engagement of said driving and driven elements so long as said device is maintained in that position.

30. In a scraper, the combination of a frame, ground engaging members supporting said frame, a pan carried by said frame and movable between digging and transporting positions relatively to said frame, lifting mechanism operable to cause movement of said pan between said positions, a friction clutch comprising a driving clutch ele-

ment connected to one of said ground engaging members and adapted for continuous rotation, and a coacting driven clutch element connected with said lifting mechanism and having a limited rotative movement, a clutch operating device, and mechanism actuated thereby for causing friction engagement of said driving and driven clutch elements when said operating device is moved to one position and for maintaining said friction engagement of the clutch elements so long as said operating device is maintained in that position.

31. In a scraper, the combination of a frame, ground engaging members supporting said frame, a pan carried by said frame and movable between digging and transporting positions, lifting means for causing movement of said pan between said positions, a driving element, clutch mechanism for operatively connecting said driving element with said lifting means, releasable locking mechanism for holding said pan in one of its positions, a control device for operating said clutch mechanism and for operating said releasable locking mechanism, and means operatively connecting said control device with said two mechanisms whereby a relatively quick movement of said control device is operative to cause actuation of one of said mechanisms and a relatively slow movement of said control device is operative to cause actuation of the other of said mechanisms.

32. In a scraper adapted to be operated by a tractor, the combination of a frame, ground engaging members supporting said frame, a pan carried by said frame and movable between digging and transporting positions, lifting means operable to move said pan between said positions, a driving element, clutch mechanism for operatively connecting said driving element with said lifting means, releasable locking mechanism for holding said pan in one of its positions, a single control rope extending from said scraper to the tractor, and means actuated by said rope for causing the operation of said clutch mechanism independently of said locking mechanism and for causing the operation of said locking mechanism independently of said clutch mechanism.

33. In a scraper, the combination of a frame, ground engaging members supporting said frame, a pan carried by said frame and movable between digging and transporting positions relatively to said frame, lifting mechanism for causing movement of said pan between said positions, a driving member, a clutch operatively connecting said driving member with said lifting mechanism, said clutch comprising driving and driven clutch elements, a clutch operating device associated therewith having a substantially circular path of movement during the engagement of the clutch, and control mechanism for the clutch comprising a track member movable substantially radially relatively to said substantially circular path of movement and adapted to actuate said clutch operating device.

34. In a scraper, the combination of a frame, ground engaging members supporting said frame, a pan, a link connection between said pan and said frame, a rotatable lifting member mounted on said frame, a lifting connection between said lifting member and said pan, means for transmitting rotative movement to said lifting member whereby in one direction of rotation of said lifting member it is operative to raise said pan from digging position to transport position, and releasable toggle lock mechanism co-

operating between said frame and said lifting member for preventing reverse rotation of said lifting member when the pan is in transport position.

- 5 35. In a scraper, the combination of a frame, ground engaging members supporting said frame, a pan carried by said frame and movable between digging, transporting and dumping positions relatively to said frame, link means for 10 establishing an operative connection between said pan and said frame, pan actuating mechanism operable to cause movement of said pan from digging position to transport position and from transport position to dumping position, and 15 mechanism for controlling the return motion of said pan from dumping position to transport position, said mechanism comprising a track surface on said frame, and a member associated with said pan adapted to engage said track surface.
- 20 36. In a scraper, the combination of a frame, ground engaging members supporting said frame, a pan carried by said frame and movable between digging, transporting and dumping positions relatively to said frame, said pan being movable to digging position by gravity, a rotatable lifting member mounted on said frame, a lifting connection between said member and
- 25

said pan, means for transmitting rotative movement to said lifting member whereby in one direction of rotation of said lifting member it is operative to raise said pan from digging position to transport position and then to tilt said pan to dumping position, and mechanism for causing the return motion of said pan from dumping position to transport position to occur substantially concentrically about the axis of rotation of said rotatable lifting member and to occur substantially concurrently with the return motion of said lifting member.

37. In a scraper, the combination of a frame, ground engaging members supporting said frame, a pan, mechanism for raising said pan from digging position to transport position and from transport position to dumping position, a draft link for establishing an operative connection between said pan and said frame, and a control link connected between said pan and said frame, 20 said draft link being under tension and said control link being under compression when said pan is engaged in digging soil, said draft link being under compression and said control link being under tension when the loaded pan is in 25 transport position.
